Primary Examiner — Susan Bennett Hattan*Assistant Examiner* — Marie Fast Horse(74) *Attorney, Agent, or Firm* — Cantor Colburn LLP(57) **CLAIM**

We claim, the ornamental design for a cartridge, as shown and described.

DESCRIPTION

FIG. 1 is a front perspective view of a cartridge, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a front perspective view of the cartridge in an environment of use.

The dotted line in the drawings depict parts of the cartridge that forms no part of the claimed design; while, the dashed lines in FIG. 8 depict environmental subject matter only and formed no part of the claimed design.

1 Claim, 5 Drawing Sheets---
